Artists.*

UNITED STATES PATENT OFFICE.

WALTER M. S. KILGOUR, OF LEXINGTON, MASSACHUSETTS.

CIRCUIT BREAKER.

Application filed February 9, 1923. Serial No. 618,103.

My invention relates to circuit breakers and although adapted particularly for use in connection with automobiles, tractors and like vehicles driven by integral combustion engines it is also adapted for use in connection with any machine or device in which it is desired a circuit will be interrupted, varied or established by changes in inclination of a part.

10 My invention which has among its objects simplicity of construction and certainty of operation will be best understood from the following description when read in the light of the accompanying drawings showing one specific embodiment of my invention selected for illustrative purposes, while the scope of my invention will be more particularly pointed out in the appended claims.

In the drawings:

20 Fig. 1 shows a longitudinal section of a circuit breaker and associated parts; and

Fig. 2 shows a section of a circuit breaker on the line 2—2 of Fig. 1 together with the mounting for the circuit breaker.

25 Referring to the drawings and to the preferred embodiment of my invention I provide a body 1 formed of suitable insulating material, as for example bakelite. The body is provided with an interior chamber 3, the bottom 5 of which, as shown in the drawings, is of conical conformation, the sides preferably, although not necessarily, when viewed in profile being straight lines. Extending into the body is a bushing 7 of insulating material, an exterior flange 9 of

30 which is received in the annular recess 11 at the upper portion of the chamber 3, this recess providing an annular shoulder which carries a gasket 13 on which the flange rests.

40 Surrounding the bushing and resting upon the flange 9 is a cap 15 the sleeve portion 17 of which is interiorly screw threaded and engages exterior screw threads about the upper portion of the body 1. In an obvious manner the cap 15 holds the bushing in assembled relation with the body.

45 Molded into the body is a stud 19 the inner flanged end of which is provided with a conical recess 21 which forms the apex of the conical bottom of the chamber 3. Extending through the bushing 7 is a pin 23 the end of which projects beyond the lower surface 24 of the bushing 7 to a point above the recess 21 and is conically shaped as shown

50 at 25 so as to present walls parallel to the walls of the recess 21. For placing the pin

and the stud in electrical communication I place in the chamber 3 a body of mercury 27 or other liquid conductor of electricity. Preferably the bottom wall 24 of the bushing 7 is so positioned that the bushing leaves a small opening between the same and the conical bottom surface 5 of the chamber 3, the corners of the bushing being beveled as indicated at 31 to eliminate the effect of wear 65 which might otherwise occur if the edge were a sharp corner.

It will be noticed that the bottom wall 24 of the bushing 7 divides the chamber 3 into a lower or primary chamber and an upper or 70 secondary chamber, the space between the bottom walls 5 and the bushing affording a restricted opening between the two chambers. It will also be noted that the bottom surface 24 of the bushing serves as a baffle 75 which will prevent undue agitation of the mercury when the device is subjected to jars or vibration and consequently will prevent accidental interruption of the circuit.

I have indicated my circuit breaker as arranged to interrupt the ignition circuit of a tractor driven by an internal combustion engine, and the circuit breaker for this purpose may be interposed at any suitable point in the circuit, as for example between the 80 battery and the coils.

For providing a convenient mounting for the circuit breaker I have shown a plate 33 which is provided with perforated ears 35 adapted to receive the ends of bolts 37 for 90 holding together the sections of the gear casing of the tractor. This plate is perforated to receive the stud 19 which projects beyond the body 1, the stud being insulated from the plate by means of the bushing 39 and 95 washer 41 of insulating material, as for example fibre. The lower end of the stud 19 is screw threaded as is indicated at 43 and carries a nut 45 for holding the circuit breaker in assembled relation with the plate 100 33.

The stud 19 serves as one terminal for the circuit breaker, the screw threaded portion 43 of the stud carrying a nut 47 which causes the stud to serve as a binding-post, as is 105 clearly indicated in Fig. 1, which shows a conductor 49 connected to the stud. The pin 23 serves as the other terminal for the circuit breaker, the same extending upwardly above the bushing 7 and carrying 110 an integral collar 51 which rests on the top of the bushing. For holding the pin

rigidly in assembled relation with the bushing I provide a metal cap 53 the interior screw threads of which engage exterior screw threads about the upper portion of the bushing and thus is enabled to clamp the collar 51 against the top surface of the bushing. Above the collar 51 the pin is screw threaded as is indicated at 55, this screw threaded portion carrying a nut 57 which 10 in conjunction with the cap 53 provides a binding-post for securing the conductor 59 to the pin.

In operation if the vehicle to which the circuit breaker is attached is tilted the mercury will flow out of the chamber below the bottom surface 24 of the bushing 7 and will interrupt the circuit when one side of the conical wall 5 assumes approximately a horizontal position, and consequently by 15 selecting body portions 1 having conical walls 5 with angles corresponding to the maximum safe inclination of the vehicle in any direction I am able to insure that the ignition circuit will be interrupted when the 20 vehicle reaches any predetermined angle of inclination from the horizontal. It will be understood that mercury is employed because of its ability to form a quick break in a satisfactory manner, the body of mercury or the portion thereof which places the contacts in electrical communication while the device is being tilted not flowing away from the contacts until the surface on which the mercury rests passes just beyond the 25 horizontal position when it immediately moves in the form of a globule away from the contacts.

Although I have described for purposes of illustration one specific embodiment of my 40 invention it is to be understood that I am not limited thereby to its particular mechanical details, but that within the scope of my invention wide deviations may be made therefrom without departing from the spirit 45 of my invention.

Claims:

1. A circuit breaker of the character described having means forming a primary and a secondary chamber, said primary 50 chamber being substantially in the form of an inverted cone and communicating with said secondary chamber through a relatively narrow slot about the periphery of the base of said inverted cone, a body of mercury in said primary chamber, a contact member in electrical communication with said body and a second contact member at the apex of said primary chamber.

2. A circuit breaker of the character described having means forming a primary and a secondary chamber, said primary chamber being substantially in the form of an inverted cone and communicating with said secondary chamber at the base of said cone, a body of mercury in said primary

chamber, a contact member in electrical communication with said body, a second contact member at the apex of said primary chamber, and said secondary chamber about the base of said cone being wider than said base. 70

3. A circuit breaker of the character described having means forming a primary and a secondary chamber, said primary chamber being substantially in the form of an inverted cone, a body of mercury in said primary chamber, means affording communication between said chambers effective to permit flowing of said body from the primary to the secondary chamber when the device is tilted in substantially any direction, and contact members at different levels in electrical communication with said body. 80

4. A circuit breaker of the character described having means forming a primary and a secondary chamber, a body of mercury in said primary chamber, means affording communication between said chambers effective to permit flowing of said body from the primary to the secondary chamber when the device is tilted in substantially any direction, and contact members at different levels in electrical communication with said body. 85

5. A circuit breaker of the character described having a body of non-conducting material formed with an interior chamber containing a body of mercury, said chamber having its portion receiving said mercury substantially in the form of an inverted cone the base of which is above the level 100 of said mercury, a contact member at the apex of said chamber, a contact member above the apex of said member, said first mentioned member being moulded into said body and having a recess forming the apex 105 of said interior chamber, and said body of mercury being in amount sufficient to form a quick break of the circuit when said body of non-conducting material is tilted to a predetermined angle. 110

6. A circuit breaker of the character described having a body of non-conducting material formed with an interior chamber containing a body of mercury, said chamber being substantially in the form of an inverted cone and being partially filled with said mercury, a contact member at the apex of said chamber and having a recess forming the apex of said chamber, a second contact member in electrical communication with said body of mercury and having its end surfaces formed to lie substantially parallel with the walls of said recess, and said body of mercury being in amount sufficient to form a quick break of the circuit when said body of non-conducting material is tilted to a predetermined angle. 115

7. A circuit breaker of the character described having a chambered body containing a body of mercury and a pair of contact 120 125 130

- members in electrical communication with said body of mercury, means forming a baffle above said body of mercury for preventing breaking of the circuit when said circuit breaker is subjected to jars or vibration, and means providing a restricted discharge for said mercury from said chamber when said chambered body is tilted. 70
8. A circuit breaker of the character described comprising means forming a chamber with bottom of substantially conical shape, a bushing extending into said chamber and having a bottom surface the periphery of which is adjacent the bottom walls of said chamber, a contact member extending through said bushing into said chamber, a contact member below the first mentioned contact member, and a body of mercury at the bottom of said chamber. 75
- 15 9. A circuit breaker of the character described having means providing a chamber for a body of mercury, terminals in electrical contact with said body, and means affording a restricted discharge from said chamber when said device is tilted in any of a plurality of substantially widely divergent planes. 80
- 20 10. A circuit breaker of the character described having means providing a chamber with a bottom wall of substantially conical shape, a contact member at the apex of said bottom wall and having a conical recess, a second contact member above said first mentioned contact member and having a conical end the surface of which is parallel to the walls of said recess, a body of mercury in said chamber, and means providing a baffle and also a restricted discharge for said mercury from said chamber. 85
- 25 11. In a circuit breaker of the character described, a body of insulating material having a chamber with a contact member at its bottom portion, said contact member having a recess, a bushing extending into said chamber in spaced relation about its periphery to the walls of said chamber and disposed above said recess, a second contact member extending through said bushing and terminating above said recess, a body of mercury in said chamber for making an electrical connection between said contact members, and said body of mercury being in amount sufficient to make a quick break of such electrical connection when said body of insulating material is tilted to a predetermined angle. 90
- 30 12. In a circuit breaker of the character described, a pair of contact members, insulating supports for said contact members, one of said contact members being recessed and the other having a surface opposite said recess, a body of mercury for putting said contact members in electrical communication, said circuit breaker providing a chamber of which chamber said recess forms the extreme bottom portion, said chamber receiving said body of mercury and permitting it quickly to break the electrical communication between said contacts by movement of a globule of mercury away from said contacts when said circuit breaker is tilted in substantially any direction to a predetermined angle, and said mercury being in amount sufficient to form such globule when said circuit breaker is so tilted. 95
- 35 13. In a circuit breaker of the character described, a pair of contact members, insulating supports for said contact members, one of said contact members being conically recessed and the other having a conical surface opposite said recess, a body of mercury for putting said contact members in electrical communication, said circuit breaker providing a chamber of which chamber said conical recess forms the extreme bottom portion, said chamber receiving said body of mercury and permitting it quickly to break the electrical communication between said contacts by movement of a globule of mercury away from said contacts when said circuit breaker is tilted in any direction to a predetermined angle, and said mercury being in amount sufficient to form such globule when said circuit breaker is so tilted. 100
- 40 14. In a circuit breaker of the character described, means forming a chamber, a contact member having a conical recess with imperforate walls serving as part of the bottom wall of said chamber, a second contact member having a conical surface with imperforate walls substantially parallel to the walls of said conical recess, and a body of mercury in said chamber establishing electrical communication between said contacts and being in amount sufficient quickly to interrupt such electrical communication by movement of a globule of mercury away from said contacts when said means forming said chamber is tilted to a predetermined angle. 105
- 45 15. A circuit breaker of the character described comprising a body of insulating material having a chamber formed therein, a contact stud about which the base of said body is molded, said stud extending below said base and having a recess at its upper end flush with the bottom of said chamber, a supporting bracket having a perforation receiving said stud, means cooperating with said stud for holding said circuit breaker in assembled relation with said bracket, a second contact member in said chamber above said stud, a body of mercury in said chamber for establishing electrical communication between said contact member and stud, and said mercury being in amount sufficient quickly to break such electrical communication by movement of a globule of mercury away from said contact member. 110
- 50 16. A circuit breaker of the character described comprising a body of insulating material having a chamber formed therein, a contact stud about which the base of said body is molded, said stud extending below said base and having a recess at its upper end flush with the bottom of said chamber, a supporting bracket having a perforation receiving said stud, means cooperating with said stud for holding said circuit breaker in assembled relation with said bracket, a second contact member in said chamber above said stud, a body of mercury in said chamber for establishing electrical communication between said contact member and stud, and said mercury being in amount sufficient quickly to break such electrical communication by movement of a globule of mercury away from said contact member. 115
- 55 17. A circuit breaker of the character described comprising a body of insulating material having a chamber formed therein, a contact stud about which the base of said body is molded, said stud extending below said base and having a recess at its upper end flush with the bottom of said chamber, a supporting bracket having a perforation receiving said stud, means cooperating with said stud for holding said circuit breaker in assembled relation with said bracket, a second contact member in said chamber above said stud, a body of mercury in said chamber for establishing electrical communication between said contact member and stud, and said mercury being in amount sufficient quickly to break such electrical communication by movement of a globule of mercury away from said contact member. 120
- 60 18. A circuit breaker of the character described comprising a body of insulating material having a chamber formed therein, a contact stud about which the base of said body is molded, said stud extending below said base and having a recess at its upper end flush with the bottom of said chamber, a supporting bracket having a perforation receiving said stud, means cooperating with said stud for holding said circuit breaker in assembled relation with said bracket, a second contact member in said chamber above said stud, a body of mercury in said chamber for establishing electrical communication between said contact member and stud, and said mercury being in amount sufficient quickly to break such electrical communication by movement of a globule of mercury away from said contact member. 125
- 65 19. A circuit breaker of the character described comprising a body of insulating material having a chamber formed therein, a contact stud about which the base of said body is molded, said stud extending below said base and having a recess at its upper end flush with the bottom of said chamber, a supporting bracket having a perforation receiving said stud, means cooperating with said stud for holding said circuit breaker in assembled relation with said bracket, a second contact member in said chamber above said stud, a body of mercury in said chamber for establishing electrical communication between said contact member and stud, and said mercury being in amount sufficient quickly to break such electrical communication by movement of a globule of mercury away from said contact member. 130

and stud when said body of insulating material is tilted to a predetermined angle.

16. A circuit breaker of the character described having a chambered body, a bushing carried by said body, said bushing extending into said chamber and dividing said chamber into two parts separated by a restricted opening, a member surrounding said bushing and cooperating with said body for holding the parts in assembled relation, a contact member extending through said bushing into said chamber, and means surrounding said contact member and cooperating with said bushing for holding said contact member and bushing in assembled relation.

17. A circuit breaker of the character described having a chambered body, a bushing carried by said body, said bushing extending into said chamber and dividing said chamber into two parts separated by a restricted opening, a member surrounding said bushing and cooperating with said body for holding the parts in assembled relation, a contact member extending through said bushing into said chamber, a collar or the like carried by said contact member and cooperating with said bushing for gauging the distance said contact member projects into said chamber, and means cooperating with said collar and bushing for holding the parts in assembled relation.

18. A circuit breaker of the character described having a chambered body, a bushing carried by said body, said bushing extending into said chamber and dividing said chamber into two parts separated by a restricted opening, a member surrounding said bushing and cooperating with said body for holding the parts in assembled relation, a contact member extending through said bushing into said chamber, and means cooperating with said bushing and contact member for gauging the distance said contact member projects into said chamber and for holding said contact member and said bushing in assembled relation.

19. A circuit breaker of the character described having a body of non-conducting material formed with a chamber containing a body of mercury, a contact member at the bottom of said chamber, a second contact member above the contact member first mentioned, means forming a discharge orifice for said mercury when said body is tilted, said orifice being restricted in one direction, a second chamber in said body for receiving the mercury discharged through said orifice, and said body of mercury being in amount sufficient quickly to interrupt electrical communication between said contacts when said body of non-conducting material is tilted to a predetermined angle.

20. A circuit breaker for the ignition circuit of an internal combustion engine driven tractor, having a body fixed to said tractor so as to tilt therewith, a chamber in said body having a conical bottom portion, spaced contacts in the bottom portion of said chamber, a body of mercury in said chamber partly filling said conical bottom portion and placing said contacts in electrical communication, and said body of mercury being in amount sufficient quickly to interrupt such electrical communication when said body is tilted to a predetermined angle.

21. A circuit breaker for the ignition circuit of an internal combustion engine driven tractor, having a body fixed to said tractor so as to tilt therewith, a chamber in said body having a conical bottom portion, means providing a baffle and restricted orifice establishing communication between the upper and lower portions of said conical bottom portion of said chamber, spaced contacts in the bottom portion of said chamber below said means, a body of mercury in said chamber partly filling said conical bottom portion and placing said contacts in electrical communication, and said body of mercury being in amount sufficient quickly to interrupt such electrical communication when said body is tilted to a predetermined angle.

22. A circuit breaker for the ignition circuit of an internal combustion engine driven tractor, having a body fixed to said tractor so as to tilt therewith, an upper and a lower chamber in said body, an annular restricted orifice establishing communication between said chambers, spaced contacts at the bottom of said lower chamber, a body of mercury in said lower chamber establishing electrical communication between said contacts, and said body of mercury being in amount sufficient quickly to interrupt such electrical communication when said body is tilted to a predetermined angle.

23. A circuit breaker having a body, a chamber in said body having a conical bottom portion, a member having a surface closely spaced relatively to the walls of said conical bottom portion to form an annular restricted exit from said bottom portion of said chamber, a pair of spaced contacts at the bottom of said chamber, a body of mercury in said chamber establishing electrical communication between said contacts, and said body of mercury being in amount sufficient quickly to interrupt such electrical communication when said body is tilted to a predetermined angle.

In testimony whereof, I have signed my name to this specification.

WALTER M. S. KILGOUR.
